CLAIM

The ornamental design for a massager as shown and described.

DESCRIPTION

FIG. 1 is a perspective view of a massager showing my design;

FIG. 2 is second perspective view thereof;

FIG. 3 is a third perspective view thereof;

FIG. 4 is a right view thereof;

FIG. 5 is a left view thereof;

FIG. 6 is a front view thereof;

FIG. 7 is a rear view thereof;

FIG. 8 is a top view thereof; and,

FIG. 9 is a bottom view thereof.

The portions of the massager shown in broken lines do not form part of the design.

1 Claim, 9 Drawing Sheets
